UNITED STATES PATENT OFFICE.

CHARLES E. BURCHFIELD, OF BUFFALO, NEW YORK, ASSIGNOR TO M. H. BIRGE & SONS CO., OF BUFFALO, NEW YORK.

DESIGN FOR WALL PAPER.

Application filed April 18, 1928. Serial No. 26,365. Term of patent 14 years.

To all whom it may concern:

Be it known that I, CHARLES E. BURCHFIELD, a citizen of the United States, residing at Buffalo, in the county of Erie and State of New York, have invented a new, original, and ornamental Design for Wall Paper, of which the following is a specification, reference being had to the accompanying drawing, forming a part thereof.

The figure is a face view of wall paper showing my new design, the figure being broken at line A—B in two sections or parts.

I claim:

The ornamental design for wall paper, as shown.

CHARLES E. BURCHFIELD.
